CENTRIFUGAL DRIER

Anton C. Schmelzer, Cleveland, Ohio

Application March 8, 1935, Serial No. 9,919

14 Claims. (Cl. 210—75)

This invention relates to centrifugal clothes rinsing and drying apparatus intended for home or domestic use and has for its principal object the provision of a machine of that type with simple and effective means for preventing water drained or thrown from the clothes basket reaching the bearings for the drive shaft, so as to permit of the use of ball or roller bearings for the shaft.

Another object of the invention is the provision of a centrifugal clothes rinsing and drying apparatus with an extracting element having its body bulging outwardly intermediate its ends and embodying extracting means in the proximity of the bulged portion and drainage means in the bottom face of the element in combination with means axially extending through the drive shaft of the extracting element for discharging the water from the basket through the shaft and prohibiting discharged water from contacting and interfering with the bearings of the drive shaft.

A still further object of the invention is the provision of an apparatus of this character, which is simple in construction, thoroughly reliable and efficient in its purpose, strong, durable, compact, readily assembled and comparatively inexpensive to manufacture and install.

With the foregoing and other objects in view, the invention consists in the features of construction, combination and arrangements of parts, as will be hereinafter more specifically described in detail and illustrated in the accompanying drawing, wherein is shown the preferred embodiment of the invention, but it is to be understood that changes, variations and modifications can be made as come properly within the scope of the appended claims without departing from the spirit of the invention or sacrificing any of its advantages.

In the accompanying drawing:

Figure 1 is a vertical fragmentary sectional view through a centrifugal clothes rinsing and drying apparatus constructed in accordance with the invention and

Figure 2 is an enlarged fragmentary sectional view through the bottom plate of the rotary basket of the apparatus disclosed in Fig. 1 showing the drainage arrangement for draining surplus water from the basket prior to extracting and drying operations.

Referring to the drawing in detail, the apparatus constructed in accordance with the invention, that is the preferred form thereof, comprises a centrifuge section A and a drive sec-

tion B. The centrifuge section A rests with its outer tank 2 upon the recessed top 3 of the drive section B and is secured thereto in a manner hereinafter described. This tank 2 encircles a double cone-shaped, rotatably mounted clothes basket 4, which basket consists of upper and lower cone portions 5 and 6 respectively, formed with outwardly extending and downwardly inclined flanges 7 and 8, secured together at spaced points by rivets 9. Flange 8 is also recessed between its points of attachment to flange 7 and forms arcuate slots 10 between the flanges 7 and 8 through which slots water is thrown by centrifugal force, when the basket 4 is rotated by a hollow drive shaft 11, arranged below in 15 the basket 4 in axial alignment with respect thereto. The lower cone portion 6 is preferably re-enforced by a cone-shaped flanged extension 12 of an adapter 14, secured to the flange 8 by the rivets 9, and is furthermore enclosed within an 20 inner tank or apron 15, which tank conforms to the configuration of and is slightly spaced from the basket 4 and the re-enforcing extension 12 of the adapter 14. This apron, at its lower end 25 rigidly secured to the top 3 of the drive section B, prevents water discharged through the slots 10 from entering into the central portion of the tank 2 and thus protects the bearing support for the hollow drive shaft 11, which shaft extends upwardly and outwardly through the top wall 3 of 30 the drive section B.

The drive section B embodies a preferably pressed sheet metal housing, comprising a cup-shaped base plate 16 and a recessed top member 17, the downturned peripheral wall 18 of 35 which is secured to the upturned flange 19 of the base plate 16. The top member 17 is supported on legs 20, extended into pockets 21 of the top member 17 and secured thereto by rivets 22. The base plate 16 rotatably mounts the hollow basket drive shaft 11, which shaft carries and is coupled with the basket 4. Thus the lower end of this drive shaft projects through an opening in a recessed portion 22 in the base plate 16 and carries a small gear 23 rigidly secured to said shaft by means of a nut 24. A tube 25, secured to the base plate 16 and partially enclosing the shaft 11, carries upper and lower bearings 26—27, which pivotally support the shaft 11. The upper end of this tube 25 projects 50 through an opening 28 in the top member 17 and is secured to said top by a flanged bracket 29 sleeved upon said tube and welded thereto, and the lower end of said tube projects through the opening in the recess 22 of the base plate 16 and 55

is secured thereto by means of a bracket 30, welded to the tube 25 and bolted to the base plate 16 by means of screw bolts 31. The lower and upper bearings 27 and 26, at opposite ends of the tube 25, which bearings are ball bearings, have their inner rings or races 33 and 32 secured to the hollow shaft 11 and a cone-shaped male adapter 34 respectively, which adapter is in turn fixed to the shaft 11, whereas the outer rings 36 and 35 of said bearings are rigidly mounted in a cup-shaped bracket 37, welded to the upper end of the tube 25, and in the lower widened end of the tube 25. The adapter 34 and a cup 34' pressed into the tube 25 form a sealed grease chamber for the upper bearing 26 and a grease cup 37' prevents grease escaping from the lower bearing 27.

The small gear 23 at the lower end of the drive shaft 11 meshes with a combined gear and friction disc 38 driven from a variable frictional speed mechanism presently described. This gear 38 which extends through a slot 39 in the wall 40 of the recess 22 for engagement with the gear 23 is mounted for rotation upon a hollow shaft 41, fixed to the base plate 16 by a nut member 42.

The variable frictional speed mechanism is adapted to be connected to and driven from a conventional wringer-type washing machine, not shown herein, but clearly illustrated and described in my co-pending application Ser. No. 688,513, filed September 7, 1933, or may be driven from any desired source of power, such as an electric motor. For such purpose the variable frictional drive mechanism includes a drive shaft 43, which shaft extends through and is rotatably mounted in a bearing housing 44, supported at its opposite ends adjacent one side of the tank 2, by means of a bracket 45 and the top member 17 of the drive section B. The upper end of the shaft 43 (not shown) may be connected to and driven from a washing machine as disclosed in the application previously referred to or may be coupled with any other source of rotary power, such as a motor, etc.

The lower end of the drive shaft 43 slidably supports a disc-shaped friction driver 46, splined to said shaft and axially movable with respect thereto, to permit of a coil spring 47, bearing at its upper end against a flanged collar 48, fixed to the shaft 43 by means of a pin 49, to yieldingly and resiliently engage and contact with an intermediate friction wheel 50. This wheel 50 is freely rotatably and axially shiftably supported upon a substantially horizontally disposed tubing or rod 52, preferably in the manner described in the application referred to above, and the rod 52 is vertically slidably mounted on hollow shaft 41 and a post 53, in turn rigidly secured to the base plate 16 by a nut 54, so as to permit of vertical adjustment of the axis of rotation of said intermediate friction wheel 50 in case of wear of its friction surface.

The intermediate friction wheel, when in its idling position, see Fig. 1, rests upon and frictionally engages an idler disc 55, pivotally mounted upon a stud shaft 56. This shaft 56 is rigidly secured to the base plate 16 by means of a nut 57.

Shifting of the friction wheel 50 from Fig. 1 position toward left by means such as for example described in the above referred to application causes frictional engagement of the friction wheel 50 with the upper face 58 of the combined gear and friction disc 38 and therewith rotation of

the shaft 11, which shaft mounts and is coupled with the cone-shaped female adapter 14 of the basket 4 by means of the male adapter 34, as will readily be seen from an inspection of the drawing.

5

The bottom face of basket 4 is centrally recessed as at 60 and perforated at 61 to permit of drainage of the basket 4 prior to and during its rotation, so as to dispose of undesired surplus water from wet clothes, dropped into the basket for drying purposes. A false bottom member 62 pressed into the recess 60 covers the opening 61 and the recess 60, so that the exposed bottom face of the basket is a plain smooth surface and permits sliding of the goods thereon without danger of tearing the goods. The false bottom member is provided with angularly offset finger portions 63, partly extended into the main body thereof to provide a series of drainage holes 64 adjacent to the edge of the recess 60, which holes permit of drainage water into the recess 60 and hence through the drainage opening 61 into and through the hollow shaft 11 to the inlet of a pump 65. To that end the basket 4 carries at the outside face of its bottom wall a short tubular member 66 rigidly connected thereto in alignment with the opening 61 by means of a flange 67, welded to said bottom wall. This tubular member 66 extends axially into the hollow shaft 11 and telescopes into a tubular member 68, extended into the lower end of the hollow shaft 11 in slightly spaced relation from the inner wall 69 thereof and the outer wall of the tubular member 66. The tubular member 68 is stationary and supported by and seated within a tubular extension 70 of a cover plate 71, bolted to the plate 16 of the drive section B by means of bolts 72. The tubular extension 70 is secured to the inlet of the pump 65 in any suitable manner, and the pump in turn is suspended from the base plate 16 by means of its flange 73, bolted to the base plate in alignment with a drain pipe 74 by means of bolts 75. The drain pipe 74 fully extends through the cover plate 71 of the drive section B and through a drain opening 76 into the tank 2 and is rigidly secured thereto by means of a collar 77, co-operating with a shoulder 78 on the drain pipe in tightly sealing the tank 2, the top member 17 and the drain pipe 74 with respect to each other.

The pump 65 consists of a two part casing 79 in which a shaft 80, carrying impeller blades 81, is adapted to be rotated by means of a bevel gear drive 82, which in turn is driven from the friction driver 46 as will be presently described. Thus the friction driver 46 carries at its circumferential surface gear teeth 83, meshing with a small gear 84 at the upper end of a freely rotatably mounted vertical shaft 85. This shaft extends through the hollow shaft 41 and is mounted near its opposite ends in upper and lower ball bearings 86 and 87. A bracket member 88, rigidly attached to the tubing 25, supports the upper ball bearing 86, while the lower ball bearing 87 is carried and supported by a gear casing 89, secured to the base plate 16 by means of bolts 90. The shaft 89, which extends into the gear casing 89, carries at its lower end a bevel gear 91, meshing with a second bevel gear 92 within the casing 89. The bevel gear 92 is attached to the end of a shaft 93, which shaft carries at its opposite end a bevel gear 94, meshing with a bevel gear 95 at the lower end of the pump shaft 80. The bevel gears 94 and 95 are mounted in a gear casing 96 secured to the pump casing 79 by means of bolts 97. Preferably the two gear casings 89 and 96 are 75.

rigidly connected by means of a steel tubing 98 in order to form a more rigid driving connection between the pump shaft 80 and the shaft 85.

When the rinsing and drying apparatus is operated the pump 65 is continuously running, that is the pump is actuated, when the basket 4 is rotated or at rest. Consequently the drainage holes in the basket will effect draining of the surplus water through the hollow shaft 11 as soon as some of the goods to be dried are placed into the basket. Rotation of the basket causes the water to ride up the outwardly flared sides of the lower half 6 and ride down the outwardly flared sides of the upper half 5 and hence out through the slots 16 between the flanges 7 and 8 into the tank 2. The inclination of the flanges 7 and 8 directs the water from the basket at an acute angle toward the vertical wall of the tank 2, prevents splashing and forming of soap suds, if the water discharged is soapy, and finally effectively prohibits water from entering the space between the apron and the basket, so that all danger of water and suds reaching the bearings is avoided. Retardation of the rotation of the basket by contact with the water or suds extracted from the clothes is also avoided.

The water thrown from the basket as well as the water drained therefrom passes to and through the pump 65 and thence either to the washing machine or to a set tub, neither of which is shown.

Having thus described my invention, what I claim is:

1. In a centrifugal drier a support, a tank having an apertured bottom mounted on said support, drive mechanism carried by said support including a hollow driven shaft extended into said tank through said apertured bottom, a basket having a perforated bottom means for connecting said basket with said driven shaft for rotation therewith and mounting said basket above and opposite the upper end of said shaft, a pump driven by said drive mechanism, and means for guiding liquid drained from said basket through said perforated bottom to said pump, said means co-operating with said hollow shaft in guiding said liquid therethrough.

2. In a centrifugal drier a support, a tank having an apertured bottom mounted on said support, drive mechanism carried by said support including a hollow shaft adapted to be driven at will and extending into said tank through the apertured bottom thereof, a basket having a perforated bottom means for connecting said basket with said driven shaft for rotation therewith and mounting same above and opposite the upper end of said shaft, a pump continuously driven by said drive mechanism, means extending centrally from the bottom of said basket for guiding liquid discharged from said basket into said hollow shaft, and means for guiding the liquid from said hollow shaft to said pump.

3. A centrifugal drier as described in claim 2, wherein said means for guiding liquid from said hollow shaft to said pump include a stationary tubing arranged within said shaft in spaced relation with respect to the inner wall thereof to permit of free rotation of said shaft.

4. In a centrifugal drier a support, a tank having an apertured bottom mounted on said support, drive mechanism carried by said support including a hollow driven shaft extended into and supported within said tank, a basket within said tank, coupling means for connecting said

shaft and basket and supporting same opposite and above the upper end thereof, said basket having its body bulging circumferentially intermediate its ends and its middle portion provided with flanged discharge openings, a skirting means encircling said basket and sealed to the bottom of the tank around its aperture said skirting means having its upper edge arranged slightly below said flanged openings for protecting said shaft and its support from liquid discharged from said basket, drainage means at the bottom of said basket, and means on said basket for guiding liquid drained from said basket into said hollow shaft for discharging said liquid therethrough.

5. In a centrifugal drier a support, a tank having an apertured bottom mounted on said support, drive mechanism carried by said support including a hollow drive shaft extended into said tank through said apertured bottom, a skirting means sealed to the bottom of the tank around its aperture, a double cone-shaped basket consisting of upper and lower flanged cone-shaped portions connected with their flanges in spaced relation to provide arcuate discharge slots therebetween, the outer ends of said slots extending laterally at an inclination beyond the upper edge of said skirting means, drainage means in the bottom face of said basket, and guiding means for guiding the drainage of said basket to and through said shaft.

6. In a centrifugal drier a support, a tank having an apertured bottom mounted on said support, drive mechanism carried by said support including a hollow driven shaft extended into said tank through said apertured bottom, a coupling member attached to said shaft, a basket, a coupling member on said basket co-operating with said first coupling member in coupling said basket with said shaft and supporting same above the upper end thereof, drainage means for said basket including means for guiding liquid from the bottom of said basket to and through said second coupling member into the upper end of said hollow shaft, and continuously driven pumping means connected with the lower end of said hollow shaft for withdrawing the liquid drained thereinto.

7. In a centrifugal drier a support, a tank having an apertured bottom mounted on said support including a hollow driven shaft extended into said tank through the apertured bottom thereof, a basket, means on said shaft and basket for coupling same with each other and supporting the basket on said shaft above the upper end thereof, drainage means at the bottom of said basket, and means on said basket for guiding liquid discharged from said basket into said hollow shaft for dispensing the liquid therethrough.

8. A centrifugal drier as described in claim 7, wherein the drainage means embody a stationary tubular member extended upwardly into said hollow shaft and spaced from the inner wall thereof.

9. A centrifugal drier as described in claim 7, wherein said drainage means include a tubular member in communication with and downwardly extended from said basket into said hollow shaft.

10. A centrifugal drier as described in claim 7, wherein said hollow shaft has upwardly extended thereinto a stationary tubular member, and wherein said drainage means include a tubular member in communication with and downwardly extended into said stationary member in said hollow shaft.

11. A centrifugal drier as described in claim 6.

wherein the coupling member on said basket is provided with an upwardly extending circumferential cone-shaped wall seating, contacting with and reinforcing the lower portion of said basket and coupling same with said coupling member.

12. In a centrifugal drier a support, a tank having an apertured bottom mounted on said support, drive mechanism carried by said support including a hollow driven shaft extended into said tank through the apertured bottom thereof, a skirting means sealed to the bottom of the tank around its aperture, a double cone-shaped basket within said tank encircled by said skirting means for connecting said basket with said shaft and supporting said basket above and opposite the upper end of said shaft, said basket having its middle portion circumferentially perforated, flanges on said basket enclosing said perforations and arranged above the upper edge of said skirting means for discharging liquid expelled by centrifugal force from said basket outwardly of said skirting means, means at the bottom of said basket for draining liquid from said basket to and through said hollow shaft, and a single pumping means in communication with said tank and said hollow shaft for dispensing the liquid from said drier.

13. A centrifugal drier as described in claim 12 wherein the coupling member at the upper end of said hollow shaft is a male member and the coupling member on the basket is a female member, and wherein said female coupling member includes an upwardly extending circumferential extension contacting with the lower portion of said basket and encircling same for reinforcing said portion, said extension being attached to one of the flanges of said basket. 10

14. In a centrifugal drier a support, a tank having an apertured bottom mounted on said support, drive mechanism carried by said support including a hollow drive shaft extended into said tank through said apertured bottom, a skirting means sealed to the bottom of the tank around its aperture to provide a ring-shaped chamber therein, a rotary basket coupled with and supported above the upper end of said shaft and adapted to expell liquid by centrifugal force and 20 direct same into said ring-shaped chamber, means at the bottom of said basket for draining liquid from said basket to and through said hollow shaft and a single pumping means in communication with said ring-shaped chamber and 25 said hollow shaft for dispensing the liquid from said drier.

ANTON C. SCHMELZER.
